[57] CLAIM

The ornamental design for a computer display or the
like, substantially as shown and described.

DESCRIPTION

FIG. 1 is an orthographic front view of the computer
display or the like showing our new design;

FIG. 2 is an orthographic rear view thereof;

FIG. 3 is an orthographic right side view thereof, the
left side being a mirror image;

FIG. 4 is an orthographic top view thereof;

FIG. 5 is a front perspective view thereof;

FIG. 6 is a rear perspective view thereof.

The base is shown in broken lines for illustrative pur-
poses only.

FIG. 1

FIG. 2

FIG. 3

FIG. 4

FIG. 6
